UNITED STATES PATENT OFFICE.

ALBERT NELSON, OF CHICAGO, ILLINOIS, ASSIGNOR TO THE AMERICAN BRAKE SHOE & FOUNDRY COMPANY, OF CHICAGO, ILLINOIS, A CORPORATION OF DELAWARE.

MOLDER'S TRUCK.

Application filed October 17, 1921. Serial No. 508,299.

To all whom it may concern:

Be it known that I, ALBERT NELSON, a citizen of the United States, residing at Chicago, in the county of Cook and State of Illinois, have invented certain new and useful Improvements in Molders' Trucks, of which the following is a specification.

The object of this invention is to provide a vehicle or conveyance equipped with molding machines and receptacles or supports for all the supplies and tools required by the molders in their work.

A further object is to provide a construction and arrangement that will place every article convenient to the molder at all times so that no time or energy is lost in securing the tools or equipment as they are needed.

Further objects will become apparent as the description is read in connection with the accompanying drawing illustrating a selected embodiment of the invention in which—

Fig. 1 is a plan view of my device; and

Fig. 2 is a side elevation looking at the lower side of Fig. 1.

As is well understood by those skilled in the art, the practice heretofore followed in foundries causes a great loss of time and energy on the part of the molder in carrying the flasks, and going after cores, chill blocks and various other supplies needed in their work. By my invention, all the equipment required for the particular job is mounted upon a truck which can be rolled along preferably over a windrow of prepared molding sand whereby one or more molders can work continuously along the sand pile and keep everything needed close to hand without taking any unnecessary steps or doing any unnecessary labor.

I have illustrated in the drawing a device which is particularly adapted for use in making brake shoes. For this work it is desirable to have a long frame cross-head supported on wheeled supports including brackets or the like 11 adjacent to each end which are provided with wheels 12 adapted to run on rails 13. The brackets 11 are somewhat V-shaped in form, and have their apices secured to the frame by the bolts 14. The brackets 11 are sufficiently high to permit molding machines 15 and 16 to be conveniently suspended from the frame 10 at the proper height for the average workman. As shown, these machines are spaced apart

sufficiently to straddle a row of molding sand and are spaced from the end frames so that the rails and frames may be far enough to each side to permit a molder to work at each machine on the side opposite to the sand pile. The molding machine 15 is for making the cope and supported above it and slightly to the left is an open-sided tray 17 adapted to receive a supply of steel backs while a box for cores 18 is carried by the brackets 19 secured to the end bracket 11. Between the box 18 and the molding machine is a shelf 20 to receive the molder's trowel and like tools. Between the molding machines 15 and 16 is a suitable fixture 21 for supporting a rammer 22. The molding machine 16 is for the drag and between it and the bracket 11 is a box 23 for chill blocks and the like, which may be suspended by the hangers 24 attached to the frame 10 by the bolts 25. A clip 26 above the machine 15 carries a supply of nails for the cores.

From the foregoing it will be seen that I have provided a truck or conveyance adapted to be moved along with the molder as he proceeds from one end of the floor to the other, and which will carry all his supplies except the sand and the flasks, thereby enabling him to accomplish his work with a minimum of lost motion. The molders will find ample room for all their movements in working about machines 15 and 16 and the man working on the cope can readily reach his steel backs in the tray 17, the cores in the box 18, or his tools lying on the shelf 20, while the man working on the drag will be within easy reach of the chill blocks in the box 23. By arranging the sand in a windrow of proper size the floor to the rear of the machine will be comparatively free from sand while the supply will always be within convenient reach.

Various changes may be made in the form, arrangement and construction of the parts without departing from the spirit and scope of the invention or sacrificing any of its material advantages, the forms hereinbefore described being merely the preferred embodiments thereof.

I claim:

1. A molder's truck, comprising a cross-head, wheeled supports for the ends of the cross-head, said cross-head being at an elevation to clear a windrow of molders' sand

on the floor of a molding room, a cope molding machine, and a drag molding machine, said machines being carried by the cross-head in spaced relation to lie at opposite sides of a windrow of molders' sand on the floor, and each of said machines being disposed in position for access thereto by a molder standing on the floor at one side of the cross-head.

10 2. A molder's truck, comprising a cross-head, brackets depending from the respective ends of the cross-head and having portions projecting in front and rear of said cross-head, wheels carried by the lower por-

tion of each bracket and disposed in front 15 and rear of the cross-head, said cross-head being at an elevation to clear a windrow of molders' sand on the floor of a molding room, a cope molding machine, and a drag molding machine, said machines being carried by the cross-head in spaced relation to lie at opposite sides of a windrow of molders' sand on the floor, and each of said machines being disposed at the rear side of the cross-head and in position for access by 20 a molder standing on the floor and at one side of the cross-head.

ALBERT NELSON.
